[57] CLAIM

The ornamental design for a fire truck crew cab, as shown and described.

DESCRIPTION

FIG. 1 is a left front perspective view of the fire truck crew cab showing my new design;

FIG. 2 is a left rear perspective view thereof;

FIG. 3 is a right front perspective view thereof;

FIG. 4 is a right rear perspective view thereof;

FIG. 5 is an enlarged right side elevational view thereof with the door open and the window raised into a partially open position; and

FIG. 6 is a left rear perspective thereof with the door open and the side window raised into a partially open position.

The broken lines in the drawing are for illustrative purposes only.
